CHARLES E. GODLEY, OF YPSILANTI, MICHIGAN, ASSIGNOR, BY MESNE ASSIGNMENTS,
TO C. M. HALL LAMP COMPANY, A CORPORATION OF MICHIGAN.

FOCUSING ADJUSTMENT DEVICE.

Application filed September 16, 1926. Serial No. 135,972.

My invention relates to a focusing device particularly suited for use in automobile headlights where the filament of the lamp bulbs need to be adjusted both longitudinally and vertically with respect to the reflector.

Generally speaking, my invention aims to provide a simple and cheaply manufactured focusing device which can easily be manipulated even by inexperienced users for affording both the longitudinal and the vertical adjustment, and one in which the two adjustments are respectively made by sliding and by tilting the lamp socket with respect to a stationary socket support, such as a reflector.

More particularly, my invention aims to provide a focusing device for this double purpose in which the movements are transmitted to the lamp socket by a resilient member which is shaped and positioned for affording a substantially straight push-and-pull effect, but which member is adapted to be flexed to rock the socket; aims to provide means operable from the exterior of the lamp casing for bodily moving the resilient member longitudinally of the lamp to secure the longitudinal adjustment, and aims to provide means independently actuated from the exterior of the lamp casing for flexing the resilient member so as to rock the socket in one direction.

My invention also aims to provide a construction of this class including a simple and easily assembled lever arrangement for flexing the resilient member, and including simple means for retaining the resilient member in operative relation to the lever when the resilient member is flexed during the attaching or detaching of the lamp bulb. It also aims to arrange the parts so that the resiliency of the resilient member will normally tend to rock the lamp bulb in one direction (and preferably in the direction which raises the lamp filament) while a movement of the lever in one direction will flex the resilient member so as to lower the lamp filament.

Furthermore, my invention aims to provide an arrangement of this class in which the resilient member guides the adjacent part of the lever so that a simple mounting will suffice for the other end of the lever, and so that the resilient member and a lever-actuating screw co-operate for holding a nut on this screw in operative relation to the lever.

Still further and also more detailed objects will appear from the following specification and from the accompanying drawings, in which—

Fig. 1 is a fragmentary central, vertical and longitudinal section through an automobile headlight equipped with a focusing device embodying my invention, showing this with the lower filament of a double filament lamp bulb substantially axial of the reflector.

Fig. 2 is a section similar to Fig. 1, but showing the focusing device adjusted to dispose the lower filament as high above the axis of the reflector as the construction will permit.

Fig. 3 is an enlarged rear perspective view of the central portion of the reflector.

Fig. 4 is a perspective view of the rear end portion of the lamp socket.

Fig. 5 is a perspective view of the bracket mounted on the lamp socket.

Fig. 6 is a perspective view of the upper portion of the lever.

Fig. 7 is a section similar to Fig. 1 but showing another embodiment of my invention.

In the embodiment of Figs. 1 to 6, the reflector 1 of the headlight has a perforation 5 of a width corresponding to the outside diameter of the lamp-socket 2 which supports the double filament lamp-bulb 4, and where the reflector is to be used with a double filament bulb the axis of the perforation is preferably somewhat above the axis 1 of the reflector. The socket 2 extends through this perforation and the perforation is vertically elongated in diameter to permit the socket to rock on its wall in a vertical plane. In a reflector of short focus, such as that here illustrated, I desirably form the portion of the reflector adjacent to this perforation into a rearwardly extending tube so as to dispose the perforation in a part somewhat behind the general surface of the reflector. For this purpose, the central part of the reflector is desirably drawn into a rearwardly extending sleeve 1^a, the bore of which tube along its horizontal axis corresponds to the outside diameter of the socket, but which bore is elongated vertically. This tube has a rear end 4 provided with a perforation 5 which has up-

per and lower parts of the same radius as the diameter of the socket and which has these parts connected by short vertical portions spaced from each other by the said diameter, as shown in Fig. 3.

This perforation also has at its bottom an enlargement forming a recess 9 to afford room for the forward arm 10 of a thrust bracket which is rigidly secured to the socket.

16 To effect this securing, I am here showing the rear end 2^a of the socket 2 as being provided with a non-circular and rearwardly directed tubular extension 2^b which extends through a correspondingly shaped perforation 11 in the vertical central part 12 of the thrust bracket, after which the rear end of this extension 2^b is flared out to clinch the bracket part 12 against the rear end of the socket.

17 Extending through the back 13 of the lamp casing from the rear of the latter is a focusing screw 14 which is threaded through the vertically extending arm 15 of an angle-shaped nut which has its other arm 16 directed toward the filaments of the lamp bulb and desirably directed slightly above a rearwardly extending arm 17 of the thrust bracket. Interposed between the said arms 16 and 17 and rigidly secured to both thereof

25 is a flat strip 18 of normally straight spring metal which forms the resilient member of any focusing device. A compression spring 19 interposed between the back 13 of the lamp casing and the vertical nut arm 15 takes up 30 any looseness between the nut and this nut arm, and also urges the focusing screw 14 forwardly so as to hold the head of this screw continuously against the rear face of the casing back 13.

40 With the parts thus arranged and with the resilient member 18 made of relatively stiff spring material, this resilient member is substantially rigid longitudinally of the lamp, so that it will readily pull the socket rearwardly when the screw 14 is rotated to draw the nut arm 15 rearwardly, and will likewise push the socket forwardly when the screw 14 is rotated in the opposite direction. Hence this affords a simple mechanism for 45 adjusting the lamp bulb longitudinally of the lamp.

To adjust the lamp filament or filaments vertically, I provide means for rocking the socket in a vertical plane about the wall of the 50 perforation in the reflector, and desirably employ a lever acting on the thrust bracket either directly or through the intermediary of the resilient member. For that purpose, Figs. 1 and 2 show a rocking lever 20 which 55 extends across the axis of the lamp socket and which has at its lower end a foot 28 mounted for rocking movement on the casing back 13.

The upper part of the lever has an edge 24 60 engaging the lower face of the resilient member 18 and this edge is preferably rounded

so that it will readily slide along the spring, and the lever has an intermediate portion trunnioned on a nut 22 threaded upon a screw 23 which extends forwardly through the casing back 13. To connect the nut 22 operatively to the lever, I preferably make the nut cylindrical (as shown in Fig. 1) and provide the lever with a rearwardly directed bend 20^a in which the nut is seated. By doing this and by disposing the lever oblique to the resilient member and inclined forwardly upward, I cause the resilient member to press the lever forwardly, thereby holding the trunnioning bend in the lever against the nut 22.

To prevent the lever from slipping laterally out of engagement with the resilient member, I provide this lever with a pair of guide fingers 25 and 25^a spaced by a distance slightly greater than the width of the resilient member and extending upwardly beyond the edge 24 at opposite sides of the resilient member, so as effectively to provide a forked upper end for the lever. Thus arranged, the guide fingers or fork arms on the lever prevent a lateral movement of the upper end of the lever, hence I can employ a simple mounting for the foot 28 of the lever, such as a pin 26 riveted to the casing back and extending loosely through a perforation in the foot 28. With the guide member or sleeve 1^a fast 95 upon the reflector, the guiding of the arm 10 of the thrust bracket by the lateral edges of the recess 9 in the sleeve prevents the socket from rotating in the sleeve, hence all parts of my device are readily kept in operative relations to one another.

However, when a lamp bulb is being inserted in, or removed from, the socket, the rearward thrust on the socket may tend to flex the resilient member considerably, and might even snap it out of the forked upper end of the lever. To guard against this, I preferably provide the lever with a stop part adapted to limit the upward movement of the resilient member with respect to the lever, such as an arm 25^b formed on the finger 25^a and extending toward the companion finger 25 but leaving a sufficient gap to permit the resilient member to be inserted into the said fork from the top of the lever. I also preferably make the lever of such an effective length that it flexes the resilient member somewhat throughout the normal range of adjustment, thereby insuring a continuous and firm pressure of the resilient member on the lever to prevent rattling and to prevent a loosening of the two adjusting screws. Thus, while Fig. 1 shows my device in a position in which the lower filament of a two-filament lamp bulb is on the axis 27 of the reflector, the resilient member is somewhat flexed and will continue to bear firmly against the edge 24 of the lever if the lower (or tilt-adjusting) screw 23 is unscrewed so as to permit the resiliency of the resilient member to 13

rock the lever forwardly and to cause the straightening of that member to rock the socket for raising the lamp filaments.

On the other hand, a rotating of the lower screw so as to draw the trunnion nut 22 rearwardly will flex the resilient member to a greater extent, as shown for example in Fig. 2, thereby rocking the socket so as to lower the lamp filaments.

10 If the reflector has a sleeve or tubular guide formation on it as above described, the upper edge of the forward end of this tubular guide can act as a stop for limiting the upward tilting of the socket, as shown in Fig. 15 2, and I preferably have the strip-connected arms 16 and 17 so disposed that the resilient member will still be slightly bowed when this maximum raising of the lamp bulb is effected.

Instead of having the tilting action transmitted through the resilient strip, I may have the lever engage a rigid part supported by the socket, as for example, by providing the thrust bracket 33 with an extension 34 engaged directly by the lever 20 as shown in Fig. 7. This latter figure also shows a spring washer 29 interposed between the casing back 30 and a pin 31 which extends through the adjusting screw 32. Thus arranged, the pin 31 and the washer 29 serve the major purpose 30 of the compression spring 19 of Fig. 1, namely that of effectively swiveling the focusing screw on the back of the casing.

With each of the two illustrated embodiments, the resilient strip need only be bowed so slightly that it will act as a substantially rigid member for transmitting longitudinal adjusting movements from the upper adjusting screw to the socket, while permitting the socket to rock readily in response to adjusting movements of the companion screw. In practice, lamp bulbs are usually adjusted first longitudinally of the lamp and the change in concentration of the projected beam is easily observed even if the filament is not in its proper vertical position. Hence the slight change in the height of the filament during the longitudinal adjusting does not interfere with the accuracy of that adjustment and the vertical position of the filament is afterwards easily adjusted by manipulating the lower screw.

However, while I have illustrated and described my invention in embodiments including desirable structural features, I do not wish to be limited to the details of the construction and arrangement thus disclosed, since many changes might obviously be made without departing either from the spirit of my invention or from the appended claims. 55 So also, it will be obvious that the perforated part of the reflector in the illustrated embodiment functions as a stationary socket supporting element by which the socket is supported with freedom for longitudinal sliding and for rocking movement and that the cas-

ing back functions as another stationary member supporting the two adjusting screws. Hence I do not wish to be limited to the use of my invention in embodiments in which this socket-supporting element forms a part of a reflector, or in which the adjusting screws are mounted on the back of a casing.

I claim as my invention:

1. In a lamp, a casing, a reflector spaced forwardly from the back of the casing and provided with a perforation, a lamp socket extending slidably through the said perforation and adapted to rock on the wall of the perforation, a flat resilient member fastened to and extending rearwardly from the socket, longitudinal adjusting means operable from the rear of the casing for bodily moving the resilient member forwardly or rearwardly, a lever pivotally mounted on the casing and extending oblique to the resilient member and slidably engaging the latter, and vertical adjusting means operable from outside the casing for rocking the lever about its said pivotal mounting.

2. A lamp construction as per claim 1, including means on the lever for limiting the movement of the lever transversely of the resilient member.

3. A lamp construction as per claim 1, in which the lever has a part forming a fork disposed so that the bottom of the fork engages the resilient member within the said fork.

4. A lamp construction as per claim 1, in which the lever has a bend intermediate its ends, and in which the vertical adjusting means comprise a nut trunnioned in the said bend and a screw interposed between the nut and the casing.

5. In a lamp, a casing, a reflector within the casing and spaced forwardly from the back of the casing, the reflector having a substantially axial perforation, a lamp socket extending slidably through the perforation and adapted to rock in a vertical plane about the wall of the perforation, a screw extending forwardly through the back of the casing and effectively swiveled upon the said back; a nut threaded on the screw, a resilient and normally straight member connecting the nut with the socket and extending longitudinally of the socket whereby rotation of the screw moves the socket longitudinally of the reflector, and means mounted upon the casing for flexing the said member to cause the latter to rock the socket about the said perforation wall.

6. In a lamp, a casing, a reflector spaced forwardly from the back of the casing and having a substantially axial perforation, a lamp socket having its axis adjacent to and extending in the same general direction as the axis of the reflector; a guide member fast on the reflector and through which the socket extends, the guide member having a portion on which the socket is adapted to rock and

also having other portions engaging the sides of the socket to limit such rocking to movement in a vertical plane; screw-actuated adjusting means interposed between the socket 5 and the back of the casing for sliding the socket longitudinally with respect to the guide member, the said means including a resilient member constructed so as to be substantially rigid longitudinally of the socket while 10 sufficiently resilient to permit a rocking of the socket; and screw-actuated means carried by the back of the casing for rocking the socket upon the guide member.

7. A lamp construction as per claim 6, in 15 which the guide means comprise a sleeve ex-

tending rearwardly from the reflector in substantial alignment with the perforation in the reflector, the said sleeve having a rear end provided with a perforation of greater height than the diameter of the socket and 20 having its lateral midheight perforation wall portions vertical and spaced from each other by the diameter of the socket.

8. A lamp construction as per claim 6, in which the guide member has a forward 25 portion disposed for limiting the rocking of the socket in one direction.

Signed at Detroit, Michigan, September 2, 1926.

CHARLES E. GODLEY.
